Primary Examiner — Prabhakar Deshmukh(74) *Attorney, Agent, or Firm* — Prakash Nama Global IP Services, PLLC(57) **CLAIM**

The ornamental design for a pair of electronic door locks, as shown and described.

DESCRIPTION

FIG. 1 is a front elevational view of a first electronic lock of the pair of electronic door locks of my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is front perspective view thereof;

FIG. 8 is a rear perspective view thereof;

FIG. 9 is a front elevational view of a second electronic lock of the pair of electronic door locks of my new design;

FIG. 10 is a rear elevational view thereof;

FIG. 11 is a left side view thereof;

FIG. 12 is a right side view thereof;

FIG. 13 is a top plan view thereof;

FIG. 14 is a bottom plan view thereof;

FIG. 15 is a front perspective view thereof;

FIG. 16 is a rear perspective view thereof; and,

FIG. 17 is a perspective view of the first and the second electronic locks of the pair of electronic door locks shown in a reduced scale after installation on a door.

The broken lines shown in FIG. 17 indicating the door form no part of the claimed design.
